(57) **CLAIM**

The ornamental design for a glove with triangular geometric projection surface texture, as shown and described.

DESCRIPTION

FIG. 1 illustrates, in upper right perspective view, an ambidextrous glove with a triangular geometric projection surface texture showing our new design, wherein the box, indicated with line 8, indicates the bounds of the detail view shown in FIG. 8;

FIG. 2 illustrates a front elevational view thereof;
FIG. 3 illustrates a back elevational view thereof;
FIG. 4 illustrates a left side elevational view thereof;
FIG. 5 illustrates a right side elevational view thereof;
FIG. 6 illustrates a top plan view thereof;
FIG. 7 illustrates a bottom plan view thereof;
FIG. 8 illustrates a detail view of area 8, as indicated in FIG. 1; and,

FIG. 9 illustrates a close-up cross-sectional view taken from line 9-9 of FIG. 8.

The broken lines in FIG. 7 represent environmental structure and form no part of the claimed design. The broken lines in FIGS. 1 and 8 demarcate the detail view and form no part of the claimed design.
